No. 36,466.

Patented July 28, 1903.

UNITED STATES PATENT OFFICE.

ALFRED JOHN MEAKIN, OF STOKE-UPON-TRENT, ENGLAND, ASSIGNOR TO
HUGH C. EDMISTON, OF NEW YORK, N. Y.

DESIGN FOR A PLATE.

SPECIFICATION forming part of Design No. 36,466, dated July 28, 1903.

Application filed June 18, 1903. Serial No. 162,141. Term of patent 3½ years.

To all whom it may concern:

Be it known that I, ALFRED JOHN MEAKIN, a citizen of Great Britain, and a resident of Wolstanton, Stoke-upon-Trent, in the county of Stafford, England, have invented a new, original, and ornamental Design for a Plate; and I do declare the following to be a full, clear, and exact specification of the same, reference being had to the accompanying drawing, forming part thereof.

In the drawing there is shown a top plan view of a plate embodying my design.

What I claim is—

The ornamental design for a plate as shown.

ALFRED JOHN MEAKIN.
